UNITED STATES PATENT OFFICE.

WM. S. KIRKHAM, OF BRANTFORD, CONNECTICUT.

BLIND-FASTENER.

Specification of Letters Patent No. 30,581, dated November 6, 1860.

To all whom it may concern:

Be it known that I, W. S. KIRKHAM, of Brantford, in the county of New Haven and State of Connecticut, have invented a new 5 and useful Improvement in Shutter and Blind Fastenings; and I do hereby declare that the following is a full, clear, and exact description of the same, reference being had to the annexed drawings, making a part of 10 this specification, in which—

Figure 1, is an outside view of a portion of a window blind with my invention applied to it; Fig. 2, a section of the same taken in the line x', x' , Fig. 1; Fig. 3, a horizontal 15 section of the same taken in the line y, y , Fig. 1; Fig. 4, a detached view of the fastening.

Similar letters of reference indicate corresponding parts in the several figures. 20 This invention relates to an improvement in the ordinary shutter and blind catches or fastenings which are employed, for securing shutters and blinds in both an open and closed state.

25 The object of this invention is to facilitate the application of the fastening to the shutter or blind—provision being made for its adaptation to the varying thicknesses of shutters and blinds as also to insure a firm and durable connection of the fastening thereto.

To enable those skilled in the art to fully understand and construct my invention I will proceed to describe it.

A, Figs. 1, 2, and 3, represents a portion of 35 a window blind to which my invention is applied.

B, is a metal tube or socket at one end of which there is a flanch or plate a . This tube B, may be described as being a cylinder 40 with its sides removed at two opposite points to form parallel planes b , one of which is shown in Fig. 4. Each plane b , is provided with a flanch c , which projects from it at right angles, and these flanches c , 45 c , are tapped to receive the inner parts of screws d , which pass through a plate C, said plate having lugs or projections e , attached which fit over the planes b , b , two over each, see Figs. 2 and 4.

50 D, is a metal bar which is secured in the tube or socket B, by a pivot f . This bar has

a spring g , bearing against it and the bar at each end is provided with a shoulder or catch h , as shown in Figs. 3 and 4.

The bar D, and spring g , are the same as 55 those in the ordinary fastenings and they therefore do not require a minute description, the operation of the bar being precisely the same as the ordinary ones, one shoulder of the bar catching over a pin on the sill 60 when the shutter or blind is closed, and the shoulder at the opposite end catching over a hook at the side of the building when the shutter or blind is open.

In order to secure this fastening to the 65 shutter or blind all that is required is simply to bore a hole through the shutter or blind at the proper point and insert the tube or socket B, in it at one end and the lugs or projections e , at the opposite end, the lugs 70 or projections fitting over the sides b , b , of the tube or socket. The screws d , d , are then passed through the plate C, and flanches c , c , and screwed up so as to draw firmly the plates C, to the sides of the shutter or blind, 75 thereby forming a firm attachment of the fastening to the former.

It will be seen that by this arrangement there will be no difficulty as regards the application of the fastening to shutters or 80 blinds of varying widths and it will also be seen that the connection of the fastening to the shutter or blind is a secure and permanent one, the shutter or blind not being liable to break or give way adjoining the fastening, a contingency which frequently occurs with the ordinary kinds.

Having thus described my invention, what I claim as new and desire to secure by Letters Patent, is:

The tube or socket B, having the bar D, and spring f , secured within it and provided with the tapped flanches c , c , in connection with the plate C, provided with lugs or projections e , and screws d , all being arranged 90 essentially as and for the purpose herein set forth.

WM. S. KIRKHAM.
